WALTER FERRIS, OF MILWAUKEE, WISCONSIN, ASSIGNOR TO THE OILGEAR COMPANY, OF MILWAUKEE, WISCONSIN, A CORPORATION OF WISCONSIN.

HYDRAULIC DRIVE FOR MACHINE TOOLS.

Application filed June 9, 1924. Serial No. 719,003.

This invention relates to continuously operated reciprocating machines and has for a general aim the provision of a drive therefor capable of effecting a marked increase in the 5 number of reciprocations per hour and insuring operation of the reciprocating part at desired speeds. Although applicable to other forms of continuously reciprocating machines this invention may be employed to 10 particular advantage in the operation of planer tables and for purposes of illustration will be described as applied thereto.

In the operation of belt driven and electrically driven planers considerable time is 15 consumed at the end of each stroke in bringing the table to rest and then returning it to full speed in the other direction. This loss of time is due primarily to the inertia of the 20 rotating driving parts and in a much smaller degree to the inertia of the reciprocating driven parts.

Two types of hydraulic drives have heretofore been proposed for use in operating planers, but neither has attained any commercial success. One type, involving a substantially constant pressure source, usually 25 a pressure accumulator, has not proven successful primarily because of the inability to maintain an accurate control of the speed of the driven part. The other type involves a reversible flow variable delivery pump, reversal being effected by reversing pump flow. This latter type is objectionable because of the time required to adjust the pump 30 through zero stroke position, from full delivery in one direction to full delivery in the other direction. The time actually required to effect this adjustment is commonly as much as three or four seconds. The time thus lost 35 in effecting reversal at each end of the stroke reduces the productive capacity of the machine when operated at moderate or even relatively long strokes, and when operated at short strokes this loss becomes very pronounced.

One specific object of the present invention is to reduce to a minimum the time required to effect the reversal. This is accomplished by the use of a hydraulic transmission drive 40 involving a hydraulic motor to which

measured quantities of driving liquid are delivered together with a valve mechanism for reversing the direction of flow to thereby effect a substantially instantaneous reversal of the motor and driven reciprocating part. 55 I have found that when a hydraulically operated piston and cylinder are employed to reciprocate a planer table, the inertia of the reciprocating parts is practically negligible as compared with the force available in the 60 form of hydraulic pressure upon the piston. Even when a rotary hydraulic motor is employed the delay in reversing is very slight, because any lag due to inertia serves merely 65 to render more effective the solid body of liquid within the motor cylinders by instantaneously raising the pressure therein. Thus in a planer driven by a hydraulic transmission mechanism, involving a valve controlled hydraulic motor whether in the form 70 of a piston and cylinder or of the rotary type, the time lag due to inertia of the driving revolving parts, which is the greatest cause of sluggishness in the belt driven and electrically driven planers will be practically 75 eliminated. By the delivery of measured quantities of driving liquid to the hydraulic motor a satisfactory control of the speed of the driven part is attained.

Another object is to further reduce the 80 time required to perform each complete cycle by effecting a high speed return of the reciprocating part after each working stroke. This is accomplished by varying the rate of 85 delivery of driving liquid to the hydraulic motor at each reversal thereof.

In the embodiment of the invention hereinafter described a variable displacement pump is employed for delivering measured 90 quantities of driving liquid to the motor, the desired high speed return of the driven part being obtained by adjusting the pump. Variable displacement pumps have heretofore been used for operating continuously 95 reciprocating machines, such as planers, but in such prior machines reversal was obtained by reversing the pump. As hereinabove pointed out such prior machines were slow to reverse due to the time required to adjust the pump through zero stroke position. By 100

interposing a reversing valve between the pump and motor to effect reversal of the motor, and by using the variable displacement function of the pump for the sole purpose of varying the operating speeds, I have rendered the machine highly productive on even short stroke work, and have in some instances doubled the productive capacity of the machine.

10 Other objects and advantages will appear from the following description of an illustrative embodiment of the present invention.

In the drawings:

15 Figure 1 is a horizontal sectional view of a planer, equipped with a hydraulic drive and control mechanism constructed in accordance with the present invention.

20 Figure 2 is a side elevation of the planer of Figure 1.

25 Figure 3 is a sectional view of a reversing valve.

30 Figure 4 is a sectional view of a portion of the control mechanism.

35 Fig. 5 is a view in elevation, partly in section, of the variable displacement pump shown in Figures 1 and 2.

40 Figs. 6 and 7 are sectional views of the valve of Figure 3 in different positions of adjustment.

45 The planer shown comprises the usual work table 10, reciprocable upon and along the horizontal ways 11, supported by the base frame 12. The usual head frame 13 provides the customary support for the usual planer tool not shown. The work table 10 carries an actuating cylinder 14 fixed to the bottom thereof and containing a piston 15 fitted for relative reciprocation therein. Hollow rods 16 and 17, extending through

50 glands 18 and 19 in the opposite ends of the cylinder, connect the piston with cross-yokes 20 and 21 secured at the ends of the ways 11. The interior of the rods 16 and 17 communicate with the opposite ends, respectively, of

55 the cylinder through ports 22 and 23, adjacent the piston. Passages 24 and 25 in the cross-yokes communicate with the respective rods. It will thus be clear that fluid pressure admitted to the left end of cylinder 14 through one of the rods 16 will cause movement of the cylinder and table toward the left, and fluid pressure admitted to the right end of the cylinder through rod 17 will move the table to the right.

60 The passages 24 and 25 are connectible with an appropriate fluid pressure source through reversing valve preferably of a type which will now be described. The valve shown comprises a valve block 26, secured to the main frame of the machine, and provided with a longitudinal bore 27. A piston valve having end heads 28 and 29 connected by a reduced portion 30 is closely fitted for lengthwise reciprocation in the bore and divides the bore into three compartments 31, 32 and 33.

A fluid supply pipe 34 communicates at all times with the intermediate compartment 32 and an exhaust pipe 35 communicates at all times with the end compartment 31. A longitudinal passage 36 through the piston valve connects the two end compartments 31 and 33. Pipes 37 and 38 leading from the passages 24 and 25, respectively, are adapted for communication with the bore 27 through ports 39 and 40 and cooperating annular chambers 41 and 42, respectively. The piston head 28 is arranged to pass over the chamber 41 from the position shown in Figure 3 to that shown in Figure 7, and is of such width as to completely cover and close this chamber in the intermediate position of the piston valve shown in Figure 6. The piston head 29 cooperates in a similar manner with the chamber 42 but is provided with short gashes 43 and 44 which extend inwardly from the ends toward an intermediate portion of the piston head 29, leaving the surface of the intermediate portion unbroken. These gashes cooperate with the chamber 42, when the piston valve is in the intermediate position of Figure 6 to effect communication between compartments 32 and 33.

65 The pipes 34 and 35 are respectively connected with the delivery and intake sides of a variable displacement pump 45 of any well known type. The pump shown is fully described in my copending application, Serial No. 682,056, filed December 21, 1923, issued October 20, 1925, Patent No. 1,558,002. It is driven at constant speed from any appropriate source of power through the pulley 46, the displacement thereof being varied and controlled by a stem or rod 47. Movement of this stem or rod toward the left increases pump displacement so as to increase the delivery of fluid therefrom to and through the pipe 34 and movement toward the right effects a corresponding decrease in pump displacement and the rate of fluid flow.

70 The valve hereinabove described and the pump control rod 47 are both placed under the control of the planer table 10 so as to automatically reverse and regulate the speed of travel of the table. In the machine shown this mechanism comprises a transverse rock shaft 48 mounted in the base frame beneath the table. An arm 49 fixed to one end of this shaft is operatively connected through a control rod 50 with the piston valve above described. Fixed adjacent the other end of the rock shaft is a rocker element 51 having a pair of laterally spaced lugs 52 and 53 projecting upwardly into the path of travel of a pair of striker elements 54 and 55 carried by the table. Each striker element is supported upon a pivot pin 56 anchored in a bracket 57 fixed to the side of the table. A compression spring 58 yieldably retains each striker element in the position shown. As the table approaches the end of its travel to-

ward the right the element 54 strikes the lug 52 and rocks the shaft 48 in a clockwise direction (Fig. 2) and as the table approaches the end of its travel in the other direction the other element 55 strikes the lug 53 and rocks the shaft in the opposite direction.

A second rocker element 59 is carried by the rock shaft 48. This element is frictionally engaged by a spring pressed disk 60 splined to the shaft, the arrangement being such that the element 59 is yieldably forced to rock with the shaft. This element carries an arm 61 connected with the pump control rod 47. The control rod passes through a lug 62 projecting from the frame of the machine and carries two stops 63 and 64 adjustably fixed thereto at opposite sides of the lug 62. Stop 63 cooperates with lug 62 to limit the movement of the control rod toward the right and stop 64 similarly limits the movement of the rod toward the left.

In the position of the parts shown in Figures 1 and 2, the table is traveling toward the right on its cutting stroke. The valve and pump control rods 50 and 47 are both in their right extreme positions so that the pump is delivering driving fluid at a relatively slow rate into and through pipe 34. This fluid is passing from pipe 34 through the intermediate compartment 32 of the valve block, and through pipe 38 and hollow piston rod 17 into the right end of cylinder 14. Fluid from the left end of this piston is returning to the pump through hollow rod 16, pipe 37, end compartment 31 and pipe 35. Table 10 continues to travel in this direction at a relatively slow rate until the shaft 48 is rocked in a clockwise direction by the action of striker element 54 against the lug 52. When this occurs the arm 49 on the rock shaft shifts the rod 50 and piston valve into the extreme left position of Figure 7. With the valve so shifted, piston head 28 closes communication between chamber 41 and compartment 31, and the intermediate portion of piston head 29 closes communication between chamber 42 and compartment 32. In this position of the valve fluid from the pipe 34 passes through the intermediate compartment 32, and through pipe 37 and hollow piston rod 16 into the left end of cylinder 14, and the planer table begins its return stroke toward the left. Fluid from the right end of the cylinder 14 returns to the pump through hollow rod 17, pipe 38, compartment 33, passage 36 in the piston valve, compartment 31 and pipe 35. Simultaneously with the shifting of the reversing valve the arm 61 on the rocker element 59 swings with the shaft 48 and pulls the pump control rod 47 toward the left until stop 64 thereon engages the lug 62. This movement of the rod 47 increases the flow of fluid in pipe 34 so that the speed of travel of the planer table is greater on the return stroke than on the working stroke.

Upon approaching the end of its return stroke, element 55 strikes lug 53, the shaft 48 and rocker elements 51 and 59 and arms 49 and 61 are rocked accordingly, the control rods 50 and 47 are returned to the positions 70 shown, and the table begins another working stroke.

The compression springs 58 behind the striker elements 54 and 55 are ordinarily compressed by the initial engagement of these 75 elements against the lugs 52 or 53, and by their subsequent reaction and expansion serve to force the rocker element 51 beyond an intermediate dead center. This action of the springs 58 and the momentum of the table 80 may ordinarily be depended upon to complete the rocking action of the rocker element and shaft 48 at the end of each reciprocation of the table.

In the machine shown, however, special 85 provision is made to insure complete reversal of the control valve in each instance. Mechanism for this purpose is shown in Figure 3. This mechanism includes a cam 65 fixed to the valve control rod 50 and provided with a 90 pair of reversely inclined faces 66 and 67. A plunger 68, reciprocable in a fixed bracket 69 secured to the main frame of the machine, carries a cam roller 70 adapted to travel upon the inclined surfaces. The roller is forced against the cam under the pressure of a spring 71. Each of the faces 66 and 67 merge into a convex surface 72 or 74, providing appropriate seats for the roller and cooperating therewith to limit the movement of the control rod 50. The arrangement is such that as the control rod is shifted toward the left from the limiting position shown, the pressure of the roller upon the face 66 offers resistance to this movement until the roller reaches and passes over the high point of the cam, after which the pressure of the roller against the face 67 assists the movement of the rod to the position in which the roller is seated against the surface 74, and the valve is completely 100 reversed. The reverse action occurs during movement of the rod and valve in the reverse direction. Any appropriate means, such as a hand lever and eccentric 75, may be provided for temporarily withdrawing the 105 plunger 68 and roller 70 out of engagement 110 with the cam.

In order that the movement of the planer may be arrested or reversed by the operator 120 at any point in its travel the rocker element 51 carries a hand lever 76 fixed thereto. By manipulation of this lever the shaft 48 may be rocked to thereby shift the valve to neutral or reverse position. It will be noted that in the neutral position of the valve the fluid delivered from the pump to and through pipe 34 enters the intermediate compartment 32 of the valve block and passes through gashes 43, chamber 42, gashes 44 and passage 36 in the piston valve to compartment 31 from 125 130

which it is returned through pipe 35 to the pump without affecting the planer table. It will also be noted that in this position of the piston valve the chamber 41 is covered by the 5 piston head 28, so as to prevent any flow in the pipe 37, and thus securely lock the planer table against accidental movement.

Although this invention is particularly adapted for planer drives and for purposes of 10 illustration and explanation has been so described, its practical application to other uses, particularly in the machine tool field, is contemplated.

I claim:

- 15 1. In a planer the combination of a reciprocating table, hydraulic means for driving said table, a variable displacement pump for operating said hydraulic means, valve mechanism interposed between said pump and hydraulic 20 means and controlled by said table for reversing the direction of travel thereof, and means controlled by said table for varying pump displacement during said reversal.
- 25 2. In a planer the combination of a reciprocating table, hydraulic means for driving said table, a variable displacement pump for operating said hydraulic means, valve mechanism controlling communication between said pump and hydraulic means, and means controlled by said table for operating said valve 30 mechanism and for simultaneously varying pump displacement to reverse and regulate the rate of travel of said table.

- 35 3. In a planer the combination of a reciprocating table, hydraulic means for driving said table, a variable displacement pump for operating said hydraulic means, means for varying pump displacement, a valve mechanism controlled by said table for reversing the direction of travel thereof to effect a working 40 stroke and a return stroke, and means controlled by said table and operable upon said displacement varying means to effect a relatively slow travel of said table during a working 45 stroke and a faster travel thereof during a return stroke.

- 50 4. In a machine tool the combination of a reciprocating member, a hydraulic drive therefor, a variable displacement pump for operating said drive, valve mechanism controlling communication between said pump and drive for reversing the direction of travel of said member, means for controlling pump displacement to regulate the speed of travel 55 of said member, and means controlled by said member for actuating said valve mechanism and for simultaneously varying pump displacement.

- 60 5. In a machine of the continuously reciprocating type the combination of a reciprocating member, a hydraulic drive therefor, means for delivering a driving liquid at a predetermined rate to said drive, valve mechanism controlling communication between said 65 means and said drive and operable to reverse

the direction of travel of said member, means for varying the rate of liquid delivered to said drive, and means actuated by said member for operating said valve mechanism and for simultaneously operating said last named 70 means.

6. In a machine of the continuously reciprocating type the combination of a reciprocating member, a hydraulic drive therefor, a variable displacement pump for operating 75 said drive, valve mechanism controlling communication between said pump and drive to reverse said member, means for controlling pump displacement, a member for operating said valve mechanism and said means, and means on said reciprocating member for actuating said last named member to reverse and regulate the rate of travel of said reciprocating member.

7. In a machine of the character described 85 the combination of a reciprocating member, means including a variable displacement pump for driving said member, valve mechanism for controlling the direction of travel of said member, a control element controlled 90 by said member for actuating said valve mechanism, and means yieldably connected with said element for varying pump displacement.

8. In a machine of the character described 95 the combination of a reciprocating member, means including a variable displacement pump for driving said member, valve mechanism for controlling the direction of travel of said member, an element controlled by said member for actuating said valve mechanism, means yieldably connected with said element 100 for varying pump displacement, and adjustable means for limiting the movement of said last named means.

9. In a machine of the continuously reciprocating type the combination of a reciprocating member, a hydraulic motor for driving said member, means for delivering measured quantities of driving liquid to said motor to effect movement of said member at a definite predetermined rate, means for varying the rate of delivery of said driving liquid to regulate the rate of movement of said member, a valve for reversing said motor, and means controlled by said member for operating said 110 valve and said rate varying means.

10. In a machine of the continuously reciprocating type the combination of a reciprocating member, a piston and cylinder for driving said member, means including a pump for delivering measured quantities of driving liquid to said cylinder to effect movement of said member at a definite predetermined rate, means for varying the rate of delivery of driving liquid to said member to regulate the rate of movement thereof, a valve for reversing the direction of flow of driving liquid to said cylinder, and means controlled by said member for operating said valve and said rate varying means.

11. The combination of a driven member, a hydraulic motor for driving said member, a pump, a pump circuit, a motor circuit, a valve casing connected with said circuits, a piston valve reciprocable in said casing for reversing said motor, said valve having a head operable when in neutral position to block said motor circuit, and a head operable when in neutral position to by-pass said pump circuit, and means for shifting said valve.
12. The combination of a driven member, a hydraulic motor for driving said member, a motor circuit, a pump, a pump circuit, and a piston valve between said circuits for controlling the direction of flow in said motor circuit, said valve comprising a casing having ports communicating with said circuits, and a piston element having spaced heads cooperating with said ports and operable when in neutral position to by-pass said pump circuit and to block said motor circuit.
13. In a machine of the character described the combination of a reciprocating member, a hydraulic motor for driving said member, a variable displacement pump, hydraulic connections between said pump and motor through which said motor is driven at a rate corresponding to pump displacement, said connections including a valve for reversing said motor, and means automatically operable at the end of each stroke of said member for operating said valve and for varying pump displacement to thereby promptly reverse and change the speed of said member.
- In witness whereof, I hereunto subscribe my name this 22nd day of April, 1924.

WALTER FERRIS.
